US00D428139S

United States Patent

[19]

Smart**Patent Number: Des. 428,139****Date of Patent: ** Jul. 11, 2000****[54] MASK FRAME**

[76] Inventor: **Gregory Scott Smart**, 30 Howard Street, Randwick, New South Wales, 2031, Australia

[**] Term: **14 Years**

[21] Appl. No.: **29/101,860**

[22] Filed: **Mar. 12, 1999**

[30] Foreign Application Priority Data

Dec. 9, 1998 [AU] Australia 3922/1998

[51] LOC (7) Cl. **29-02**

[52] U.S. Cl. **D24/110.4; D24/110.5**
